DESIGN FOR AN OVEN DOOR HANDLE

Edwin W. North, Rockford, Ill., assignor to National Lock Company, Rockford, Ill., a corporation of Delaware

Application June 18, 1945, Serial No. 120,173

Term of patent 7 years

(Cl. D81—25)

To all whom it may concern:

Be it known that I, Edwin W. North, a citizen of the United States, residing at Rockford, in the county of Winnebago and State of Illinois, have invented a new, original, and ornamental Design for an Oven Door Handle, of which the following is a specification, reference being had to the accompanying drawing, forming part thereof.

In the drawing,

Fig. 1 is a plan view of an oven door handle embodying my new design;

Fig. 2 is a front elevation thereof;

Fig. 3 is a bottom view; and

Fig. 4 is a rear elevation thereof.

I claim:

The ornamental design for an oven door handle, substantially as shown.

EDWIN W. NORTH.
